UNITED STATES PATENT OFFICE.

THOMAS J. MURDOCK, OF FRANKLIN, MASSACHUSETTS, ASSIGNOR TO MURDOCK & GEB COMPANY, OF FRANKLIN, MASSACHUSETTS.

BOBBIN-HOLDER.

SPECIFICATION forming part of Letters Patent No. 783,729, dated February 28, 1905.

Application filed February 3, 1904. Serial No. 191,877.

To all whom it may concern:

Be it known that I, THOMAS J. MURDOCK, a citizen of the United States, residing at Franklin, in the county of Norfolk and State of Massachusetts, have invented a new and useful Improvement in Bobbin-Holders, of which the following is a specification.

This invention has reference to an improvement in bobbin-holders used to secure bobbins to the spindles of spinning-mules or spinning-machines.

The object of my invention is to simplify and strengthen the construction of an automatic bobbin-holder adapted to securely clamp the bobbin to the spindle by a downward movement of the bobbin on the spindle and to release the bobbin by an upward movement of the bobbin by the operator.

My invention consists in the peculiar and novel construction of an automatic bobbin-holder having clamping-arms shaped to enter the peripheral groove in the head of the bobbin, said arms being held in their contracted position under spring tension by an annular coil-spring, and means for pivotally securing the clamping-arms to firmly support the same and to allow a limited in-and-out movement of the arms in the holder, as will be more fully set forth hereinafter.

Figure 1 is a vertical view of a spindle provided with my improved automatic bobbin-holder, showing a full bobbin secured to the spindle by the holder. Fig. 2 is an enlarged plan view of the clamping-arms shown in the position they would assume when assembled in the holder. Fig. 3 is a top view of the pivot-plate. Fig. 4 is a top view of the locking-plate. Fig. 5 is a transverse sectional view taken on line X X of Fig. 1 through the holder looking upward, showing the lower ends of the clamping-arms held in their relative position in the holder by the pivot-plate. Fig. 6 is a vertical sectional view taken centrally through one of the clamping-arms in the holder, showing the construction of the holder and bobbin-head. Fig. 7 is a perspective view of one of the clamping-arms looking at the inside of the arm. Fig. 8 is an en-

larged detail sectional view taken on line Y Y of Fig. 3, showing one of the upwardly-bent ends on the pivot-plate; and Fig. 9 is an enlarged detail sectional view taken on line Z Z of Fig. 4, showing the shape of the offsets on the locking-plate.

In the drawings, *a* indicates the bobbin, *b* the spindle, and *c* my improved automatic bobbin-holder. The bobbin *a* has the head *a'*, in which is the usual peripheral groove *a''*. The fixed parts of the holder are secured together by the ring *d*, formed like an eyelet, 55 having the head *d'* to form a shoulder and the whole secured to the spindle by driving the ring *d* onto the spindle. The frame *e* of the holder has the central hole *e'* in the bottom, through which the ring *d* extends, 60 the openings *e''* *e'''* in the bottom under the clamping-arms, and the upwardly-extending circular rim *e''*.

The pivot-plate *f* has the central hole *f'* for the ring *d* and the arms *f''* *f'''* with the upwardly-bent ends *f''''* *f'''*, the arms being shaped to form the recessed openings *f''* *f'''*, in which the lower ends of the clamping-arms are held. The clamping-arms *g* *g*, the construction of which is clearly shown in Fig. 7, have the lower ends *g'* shaped to loosely fit the recessed openings *f''* *f'''* in the pivot-plate *f*, the central slot *g''* extending through the side and lower end of the arm and the upper outwardly-turned lipped end *g'''* shaped to enter the peripheral groove *a''* in the bobbin-head and to hold the annular spring *i* in its operative position on the clamping-arms. The locking-plate *h* has the central hole *h'* for the ring *d* and the upwardly-turned offsets *h''* *h'''*. 85

In assembling the parts of my improved bobbin-holder the lower ends *g'* *g''* of the clamping-arms are placed in the recessed openings *f''* *f'''* of the pivot-plate *f* between the bottom of the frame *e* and the locking-plate *h*. The ring *d* is now passed through the central holes in the frame *e*, the pivot-plate *f*, and the locking-plate *h* and the whole secured together by upsetting the upper end of the ring *d* onto the locking-plate *h*. The upwardly-bent ends *f''''* *f'''* on the pivot-plate *f* 95

bear on the sides of the clamping-arms, and the offsets h^2 h^3 on the locking-plate h enter the slots g^2 g^3 in the arms, forming guides and supports for the arms and preventing side movement of the arms. The pivot-plate f is thicker than the lower end of the clamping-arms, thus giving a predetermined amount of play for the lower end of the arm between the bottom of the frame e and the locking-plate h and limiting the in-and-out movement of the clamping-arms. The upwardly-extending rim e^3 on the frame e also limits the outward movement of the clamping-arms.

In the operation of my improved bobbin-holder a downward movement of the bobbin on the spindle by the operator brings the head of the bobbin between the clamping-arms, forcing them outward against the tension of the annular spring i until the upper ends of the arms enter the groove in the head of the bobbin, securely holding the bobbin on the spindle, and an upward movement of the bobbin by the operator is all that is required to release the bobbin from the holder.

In the preferred form, as shown in the drawings, I use a construction embodying three clamping-arms. It is evident that this construction could be so varied that four clamping-arms could be used, if desired, without materially affecting the spirit of my invention.

Having thus described my invention, I claim as new and desire to secure by Letters Patent—

1. In a bobbin-holder, a plurality of clamping-arms formed with slots, means for pivotally securing the arms in the holder, and means for supporting the arms laterally in the holder, and a plate having offsets adapted to enter the

slots in the clamping-arms and prevent side movement of the clamping-arms, as described.

2. In a bobbin-holder, a plurality of clamping-arms, a pivot-plate in which the clamping-arms are pivotally supported provided with upwardly-bent arms adapted to bear on the sides of the clamping-arms, a locking-plate, and means for securing the locking-plate and pivot-plate together, as and for the purpose described.

3. In a bobbin-holder, a plurality of clamping-arms formed with slots, means for pivotally securing the arms in the holder, and means for supporting the arms laterally in the holder, a plate having offsets adapted to enter the slots in the clamping-arms, and a plate having upwardly-bent arms adapted to bear on the sides of the clamping-arms, as described.

4. In a bobbin-holder, a plurality of the clamping-arms g , formed with slots g^2 , means for pivotally securing the arms in the holder, consisting of the frame e , the pivot-plate f , and the locking-plate h , and means for supporting the arms laterally in the holder, the locking-plate h having the offsets h^2 adapted to enter the slots in the clamping-arms, the pivot-plate f having the upwardly-bent arms f^3 adapted to bear on the sides of the clamping-arms, and means for exerting a spring tension on the clamping-arms, as described.

In testimony whereof I have signed my name to this specification in the presence of two subscribing witnesses.

THOMAS J. MURDOCK.
